UNITED STATES PATENT OFFICE.

GEORGE H. HAMMONS, OF GARDEN CANYON, ARIZONA.

HANDLE FOR HEADLIGHT RIMS.

Application filed September 16, 1924. Serial No. 738,060.

This invention relates to an improved rim handle for motor vehicle headlights and seeks to provide a means whereby the rims of such headlights may be readily rotated 5 and removed.

The invention further seeks to provide a handle which may be readily attached to the rims of conventional headlights without the necessity for structural change therein.

10 And the invention still further seeks to provide a handle which will be ornamental.

Other and incidental objects will appear hereinafter.

In the accompanying drawings:

15 Figure 1 is a perspective view showing the headlights of a conventional motor vehicle equipped with my improved handle.

Figure 2 is a detail elevation showing the manner in which the handle is applied, a 20 portion of a headlight rim being shown in section,

Figure 3 is a detail sectional view on the line 3—3 of Figure 1, looking in the direction indicated by the arrows, and

25 Figure 4 is a detail sectional view showing a slight modification in the mounting of the handle.

As is well known, the front rims of motor vehicle headlights are more or less difficult 30 to remove and this is particularly true in any case where the headlights have been in use for a considerable length of time. Under prevalent practice, the headlight casings are provided with bayonet slots and the front 35 rims are provided with studs to engage in said slots while suitable springs or other yieldable elements are provided between the front rims and the casings for pressing outwardly on the front rims frictionally locking the rims against rotation. Accordingly, 40 it is necessary, in order to remove a rim, to not only rotate the rim but also simultaneously press inwardly thereon. Since the rims are usually smooth and hard to grasp, this 45 operation is difficult and it not infrequently happens that the front lens of the head light is broken. Furthermore, owing to the usual 50 difficulty encountered in removing the front rim of a headlight, the replacement of a burnt out light bulb in the headlight is neglected, with ensuing accidents. The present invention, therefore, seeks to overcome 55 these various difficulties.

In the drawings, I have shown my improved handle in connection with the usual 60 drum headlights of a conventional motor

vehicle. The headlight casings are indicated at 10, the front rims thereof at 11, and the front lenses at 12, the lenses being carried by the rims and being removable therewith. 60 Formed in the casings 10 at their forward margin are suitably spaced bayonet slots 13, as seen at the left of Figure 1, and mounted on the rims 11 to removably engage in said slots are, as illustrated in Figure 3, pins 65 14. In the present instance, I have shown the use of yieldable gaskets 15 between the front lenses 12 and the forward edges of the casings. However, as previously intimated, appropriately arranged springs are 70 often employed in lieu of such gaskets.

Coming now more particularly to the subject of the present invention, my improved handle is, as shown in Figure 2 of the drawings, substantially of the shape of the letter 75 M. A suitable resilient rod is preferably employed to form the handle and said rod is bent to produce an intermediate loop 16 while the end portions of the rod are again bent to form parallel legs 17. The configuration of the handle may, of course, be varied, but I have adopted the shape illustrated since the handle is thereby rendered somewhat unique as well as ornamental and, 80 preferably, the rod from which the handle is formed is hexagonal in cross section. Formed on the legs 17 at their lower ends are reduced studs 18, at the base ends of which are defined shoulders 19. As shown in Figure 2, the studs 18 are inserted through 85 the headlight rim, when said studs are upset for rigidly connecting the handle with the rim. If preferred, however, the legs may, as illustrated in Figure 4, be formed at their lower ends with reduced studs 20 90 which are bored axially to receive cap screws 21, the heads of which overhang the studs to coact with the rim so that the screws may thus be adjusted for tightly binding the handle in position. In thus employing 95 the screws, the handle may, of course, be applied with facility or easily removed.

As shown in Figure 1, a pair of handles 100 is preferably employed upon each headlight rim, the handles being suitably spaced circumferentially of the rim. Accordingly, as will be seen, the handles may be readily grasped and inward pressure exerted upon the handles for shifting the rim inwardly which, as before stated, is usually required, 105 when the rim may be turned and removed. Removal of the rims may thus be easily

and quickly accomplished without danger of fracturing the headlight lenses.

It is well-known that the removal of the lens-retaining rim of a headlight of the character set forth in which pressure must be exerted thereon to release the parts, it is essential that the rim be simultaneously rotated to effect disengagement of the locking elements. The initial and continued inward pressure upon the rim frequently results in damage to the fragile lens and this is overcome by the present invention in the provision of the intermediate portion 16 of the handle which is yieldable to equalize the pressure while preventing violent application thereof with the chances of serious injury to the lens. The side elements formed by the end portions of the rod constitute hand grips to sustain the force exerted when rotating the rim to disengage or engage the locking elements as occasion may require. It is observed that the rod providing the handle is reversely bent so that the inwardly extending loop 16 forms the pressure sus-

taining element to prevent injury to the lens when releasing the locking elements by pressing inwardly upon the lens retaining rim. The side elements enable the hand to obtain a firm grip upon the handle and provide effective means for rotating and otherwise manipulating the rim.

Having thus described the invention, what I claim is:

A headlight, comprising a casing and a lens retaining rim detachably fitted to the casing by a combined inward pressure and rotative movement, and a handle on the rim and consisting of a rod reversely bent to provide an intermediate loop-shaped pressure sustaining element and outer hand gripping elements which are attached at their inner ends to the rim, the loop-shaped element being suspended between and serving to connect the outer ends of the hand gripping elements.

In testimony whereof I affix my signature.

GEORGE H. HAMMONS. [L. S.]
